UNITED STATES PATENT OFFICE.

JOSEF HOFMANN, OF BAUMAROCHE, SWITZERLAND.

NEUMATIC CUSHION.

1,089,537.

Specification of Letters Patent. Patented Sept. 24, 1912.

Application filed September 6, 1911. Serial No. 647,945.

To all whom it may concern:

Be it known that I, JOSEF HOFMANN, a subject of the Emperor of Austria-Hungary, residing at Baumaroche, Switzerland, have invented certain new and useful Improvements in Pneumatic Cushions; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to pneumatic springs for vehicles, more especially for motor vehicles, in which a pneumatic diaphragm is arranged within a rigid receptacle or casing and coöperating with a plunger.

In pneumatic cushions hitherto in use the size of the opening of the casing which is closed by the diaphragm and plunger remains constant during the whole stroke of the plunger.

By applying steel springs within the casing the smoothness of the resiliency which is especially of advantage in pneumatic cushions is diminished. Compression of the air on the other hand results and produces heat that damages the material of the diaphragm. Another drawback of these pneumatic cushions is the unfavorable stress on the material of the diaphragm caused by the diaphragm becoming folded or creased.

One object of the present invention is to so construct the spring or cushion, that there takes place from the neutral position of the same a continual increase of the effective diameter of the receptacle which is closed by the diaphragm and the plunger, and thereby increasing the effective pneumatic pressure on the piston member or plunger.

A construction according to this invention is illustrated by way of example in the accompanying drawing in which—

Figure 1 is a longitudinal section through the pneumatic cushion. Fig. 2 is a longitudinal section on line B—B of Fig. 1. Fig. 3 illustrates the working of the device. Fig. 4 shows the same mounted on a vehicle.

The cylinder member or casing 1 of rigid material is mounted on the frame 18 of a car (Fig. 4). The casing (Fig. 1) consists

of two parts of different diameters which are connected to each other by a conical part. For making the best use of the available space between the frame and the wheels of the car, the casing 1 will preferably be of oblong cross-section as will be seen from Fig. 2. To the lower part of the casing 1 is secured a box 2 with a lining 3 which forms a guide for a tube 4. A piston member or plunger 5 being screwed to the upper end of the tube 4 is essentially of conical shape, rounded off on the top and provided inside with a spherical recess 6 forming a bearing for the upper spherical journal of a supporting rod 7. The lower spherical journal of the rod 7 is suitably supported by a plate 8 secured to the axle 9 of the vehicle or otherwise. The upper end of the casing 1 is provided with a flange 11 to which is secured a vaulted cover 13 by means of bolts 12.

The edge of a pneumatic diaphragm 14 is held tight between the flanges of the casing 1 and the cover 13. The diaphragm 14 may consist of any suitable material as layers of fabric alternating with layers of rubber for instance. The diaphragm partly rests against the inner wall of casing 1 and partly against the plunger 5. A pin 16 is vulcanized to the diaphragm 14 and engages a notch provided at the top of the plunger 5, whereby sliding of the diaphragm on the plunger is prevented.

A completely air-tight chamber A is formed by the above described arrangement. This chamber is filled with air and is connected to an air chamber 19 by a pipe 15.

A pneumatic spring as described above is provided at every wheel of the vehicle.

Any suitable number of air-chambers may be applied, one air chamber may be provided for every spring or for every axle, or all springs may be connected to one and the same air chamber for instance.

The device acts as follows: A pressure exerted from below on the axle 9 causes the plunger 5 to enter somewhat more into the chamber A. Hereby a part of the diaphragm 14 is taken from against the casing 1 and put against the plunger 5. In so doing, the effective area of the movable parts, piston and diaphragm is increased, so that the total pressure on the piston increases as the piston rises in the casing. The

air escapes by the pipe 15 to the air chambers so that no considerable increase of pressure or compression will result in the chamber A. Heating of the air and damage of the diaphragm material is prevented.

5. The conical shape of the middle part of the casing and the conical plunger cause the part 17 of the diaphragm which is exposed to a dangerous pressure, to be maintained 10 very small and it remains approximately the same for all positions of the plunger (Fig. 3). There also takes place from the neutral position of the plunger to the upper end position of the same a continual increase 15 of the area acted upon by compressed air. This is of great advantage for the reason that as the load on casing 1 increases the plunger moves into the casing with an increasing effective area, so that with a substantially uniform pressure on this area the 20 spring accommodates itself automatically to varying loads.

By guiding the plunger 5 and by supporting the rod 7 in the described manner by 25 spherical journals shocks exerted laterally on the axle 9 are diverted into the direction of motion of the plunger.

The above described construction of the pneumatic cushion allows the application 30 of a large stroke, which may be directed upward as well as downward.

I claim:

1. In a pneumatic spring, the combination with an air cushion formed between oppositely movable members of said spring, and 35 whose effective area varies directly with the load when the members move relatively to one another in either direction from their normal positions of a closed air chamber 40 communicating with the air space between said members and into which the air between said members is displaced as they move toward one another thereby maintaining the pressure of air between the members 45 substantially constant under all conditions of operation.

2. In a pneumatic spring, a cylinder member, a piston member movable longitudinally in either direction from its normal position 50 and a diaphragm between the members, the effective area of the diaphragm increasing with the increase of the load as the two members approach one another, and means to maintain the air pressure per unit area 55 of the diaphragm approximately constant.

3. In a pneumatic spring, a cylinder member, a similar piston member and a flexible diaphragm extending across the cylinder member, and both members having tapered 60 walls diverging from one another toward the interior of the cylinder member.

4. In a pneumatic spring, a cylinder member, a similar piston member and a flexible diaphragm extending across the cylinder 65 member and both members having tapered

walls diverging from one another toward the interior of the cylinder member, and means to maintain the pneumatic pressure per unit area approximately constant.

5. In a pneumatic spring, the combination 70 with a cylinder member, a piston member and a flexible diaphragm between the members, of a supporting rod for the piston member, and a support for the rod, the ends of said rod being free to rock in any direction with respect to piston member and the support.

6. In a pneumatic spring, the combination with a cylinder member, a piston member and a flexible diaphragm between them, of 80 a pipe connected to the piston member, means to guide the pipe, a supporting rod for the piston member passing through the pipe and means to support the lower end of the rod, the ends of the rod having universal 85 movement with respect to the elements contacting therewith.

7. A pneumatic spring comprising a piston member having a tapered head, a cylinder member having tapered walls and diverging with respect to each other, a flexible diaphragm between the members, means to maintain the pneumatic pressure per unit 90 of area substantially constant, a rod support, a rod having universal engagement 95 with the piston member and the rod support, a pipe connected to the piston member and surrounding the rod, and a guide secured to the cylinder member for said pipe.

8. In a pneumatic spring, a cylinder member, a piston member in the cylinder arranged to move longitudinally in either direction from its normal position, and a diaphragm between the members, the effective areas of said piston member and diaphragm 105 varying directly with the load.

9. In a pneumatic spring, a cylinder member, a piston member in the cylinder arranged to move longitudinally in either direction from its normal position, and a diaphragm between the members; the effective areas of said piston member and diaphragm 110 varying directly with the load, and means to maintain a substantially constant pressure per unit area on said diaphragm.

10. In a pneumatic spring, a cylinder member having diameters transverse to one another of different lengths, and a wall tapering inward, a similar piston member having a wall diverging from the tapering cylinder 120 wall and movable up and down from normal position relatively to the cylinder member, a diaphragm between and supported by said tapering and diverging walls, whereby the effective area of the diaphragm under 125 the pressure of the air varies directly with the load, and means to maintain the pneumatic pressure per unit area substantially constant.

11. In a pneumatic spring, a cylinder mem- 130

ber, a piston member in the cylinder member arranged to move longitudinally in either direction from its normal position, a diaphragm between the two members, said members having diaphragm-supporting walls diverging from each other that increase the effective area of the piston and diaphragm as the piston member enters the cylinder member and vice versa, an air

chamber, and means to connect the air space 10 in the cylinder member with said chamber.

In testimony that I claim the foregoing as my invention, I have signed my name in presence of two subscribing witnesses.

JOSEF HOFMANN.
